UNITED STATES PATENT OFFICE.

OTTO PARTENHEIMER, OF NEW YORK, N. Y.

DESIGN FOR A CIGAR-HOLDER AND ASH-RECEIVER.

42,858.

Specification for Design.

Patented Aug. 6, 1912.

Application filed April 27, 1912. Serial No. 693,742. Term of patent 3½ years.

To all whom it may concern:

Be it known that I, OTTO PARTENHEIMER, a citizen of the United States, residing at No. 1066 Forest avenue, borough of the Bronx, in the city, county, and State of New York, have invented a new, original, and ornamental Design for Cigar-Holders and Ash-Receipters, reference being had to the accompanying drawing, forming part hereof.

The figure is a side elevation showing my new design of a cigar holder and ash receiver.

I claim:

The ornamental design for a cigar holder and ash receiver as shown.

OTTO PARTENHEIMER.
